UNITED STATES PATENT OFFICE.

FRANK H. MARKER, OF CHICAGO, ILLINOIS, ASSIGNOR TO THE PAN CONFECTION COMPANY, OF SAME PLACE.

LOZENGE-MAKING MACHINE.

SPECIFICATION forming part of Letters Patent No. 644,931, dated March 6, 1900.

Application filed June 26, 1899. Serial No. 721,807. (No model.)

To all whom it may concern:

Be it known that I, FRANK H. MARKER, a citizen of the United States of America, and a resident of Chicago, county of Cook, State 5 of Illinois, have invented certain new and useful Improvements in Lozenge-Making Machines, of which the following is a specification.

My invention relates to lozenge-making machines, and has for its object the construction 10 of a machine which will receive the so-called "dough," roll it out to a required thickness, make required prints on the dough at regular points, cut the lozenges from the printed 15 dough, and finally deliver the printed and cut lozenges upon trays.

In the accompanying drawings, Figure 1 is a side elevation. Fig. 2 is a plan. Fig. 3 is an enlarged longitudinal section showing the 20 construction of the main parts of the machine; and Figs. 4 to 8 are enlarged details, to be referred to in the description.

In the said drawings, 10 is a framework for supporting the operating mechanism. At a 25 suitable point on the frame 10 is a drive-shaft 11, which communicates power to the crank-shaft 12 by gears 13.

Located at the front and upper part of the machine are two rollers 14 and 15, which 30 carry a heavy receiving-belt 16. Located farther to the rear are two other rollers 17 and 18, which carry a heavy inclined belt 19. Between the rollers 15 and 17 is another roller 20, and over this is a roller 21. The rollers 35 14 and 18 are adjustable in horizontal and inclined directions, respectively, for the purpose of tightening the belts 16 and 19, and the roller 21 is adjustable in a vertical direction. (See Figs. 1, 6, and 7.) The rollers 15, 40 17, 20, and 21 are connected together by a train of gearing 22, which causes them to turn in the directions illustrated by the arrows in Fig. 3. On the shaft that carries the central roller 20 is a ratchet-wheel 23, and pivoted on 45 the same shaft is an arm 24, that carries a pawl 25 for engaging this ratchet-wheel. On the end of the shaft 12 is a crank 26, from which a pitman 27 connects to the arm 24 to move it. The connection between the pitman 50 27 and the arm 24 is by means of an adjustable block 28 for varying the stroke of the

arm 24, and consequently the distance the rollers are moved per revolution of the shaft 12. At or near the center of the shaft 12 is a second crank 29, from which a pitman 30 55 connects to a rock-arm 31, secured to the rock-shaft 32. The other end of the rock-arm 31 is provided with a rod 33, which connects to another rock-arm 34 on the shaft 35. Between the rod 33 and rock-arm 34 is another 60 adjustable block 36 for varying the stroke of the rock-arm 34. The upper end of the rock-arm 34 branches out into two arms 37, in which are held a series of removable lozenge-cutters 38. The relationship of the connections from 65 crank 29 to each other is such that the lozenge-cutters are moved from the position shown in the drawings to contact with the belt 19 at a point a little above the idle roller 18. The lozenge-cutters 38 are not held directly by the arms 37, but by a cross-bridge 39, which is provided with a rearwardly-projecting shelf 40. On the inclined part of the frame 10, near the belt 19, are two standards 41, between which is supported a polygonal 70 ink-pad 42. Below the ink-pad 42 is a printing-frame 43, to the ends of which are secured the gear-segments 44, that slide up and down in the standards 41. On each standard 41 is a section of a rack 45, adapted to engage the 75 segments 44, so as to turn them, and consequently the printing-frame 43, a half-revolution while ascending or descending. (See Figs. 1, 4, and 5.) Pivoted near each end of the printing-frame 43 are two rods 46, which extend downward and connect to two rock-arms 47, secured near the ends of the rock-shaft 32. The action of these parts is that the motion of the rock-shaft 32 is communicated to the printing-frame, so as to reciprocate it between the ink-pad 42 and the belt 19. By securing rubber type to the printing-frame any desired printing can be put upon anything carried on the belt 19.

At the rear of the frame 10 is an extension 95 50, which may reach out any required distance and be supported from the floor in any convenient manner. On the extension 50 are brackets 51 and 52. In the brackets 51 are pivoted the adjustable rods 53, between the 100 lower ends of which is suspended one end of an inclined table 54. The other end of the

table 54 rests on a roller 55, supported between brackets 52. On a shaft 56, supported in the frame 10, is an eccentric 57, the rod 58 of which connects to a lug 59 on the bottom 5 of the table 54. Power is communicated to shaft 56 from shaft 12 by means of belts 60 and 61 and intermediate shaft 62. On the intermediate shaft 62 is a roller 63, which carries a belt 64, running over a similar roller 10 at any required distance away. On the belt 64 are placed trays 65, which move in the direction of the adjacent arrow and under the lower end of the table 54.

In operation the dough is placed on the belt 15 16 and the roll 21 is adjusted downward toward the roll 20, so as to give the right thickness to the material as it passes between the said rolls. The block 28 is then adjusted on the arm 24, so that the forward feed of the 20 rolls and belts will be appropriate for the size of lozenge to be cut. The required lozenge-cutters are secured to the arms 37, and suitable type or stamps are secured to the printing-frame 43. To make the printing and cutting 25 register for different feeds, the standards 41 may be made adjustable. I have shown the standards 41 with wide bases, which are slotted, as shown in Fig. 5, for permitting this adjustment. Once for each revolution of the 30 crank-shaft 12 the rolls and belts 16 and 19 feed the material forward, the printing-frame moves downward and puts a row of impressions upon the material on the belt 19, and the cutters 38 come forward and cut out a 35 row of impressions previously stamped. As the cutters are thrown back the cut lozenges are thrown out over the shelf 40 onto the reciprocating table 54. The reciprocations of the table 54 cause the cut lozenges to move 40 gradually downward and be deposited on the tray that is moving slowly forward under the lower end of said table. The belt 16 is a heavy one, so as to easily carry whatever material may be placed upon it. The belt 19 is 45 also a heavy one, but for a different purpose. It is on the belt 19 that the printing and cutting are done. By printing upon a belt for a base the movement of the printing-frame need not be very accurately adjusted, as the yield 50 of the belt will accommodate variations of thickness or stroke, and thus secure a good print without danger of mashing the material. By cutting the lozenges upon a belt at a point slightly removed from the roller or 55 pulley over which it runs sufficient stiffness or strength of base may be secured for cutting the material, and yet sufficient yielding may be had to avoid cutting the belt or base.

What I claim is—

60 1. In a lozenge-cutting machine, a belt, means for giving said belt an intermittent movement so as to convey material intermittently, a printing device and means for oper-

ating it so as to print upon the intermittently-moving material, a series of cutters and means 65 for moving them so as to cut the printed material, means for adjusting the stroke of said cutters, and means for adjusting the position of said printing device.

2. In a lozenge-cutting machine, means 70 for moving lozenge material intermittently through said machine, a printing device adapted to print upon the material so moved, a series of cutters and means for moving them so as to cut the printed material, and means 75 for permitting the distance between said printing device and said cutters to be adjusted.

3. In a lozenge-cutting machine, a pair of rollers and a belt carried thereby, means for 80 giving said belt an intermittent forward motion, a printing device adapted to print upon material carried by said belt, a series of cutters and means for moving them so as to cut such material, and means for varying the distance 85 between said printing device and said cutters.

4. In a lozenge-cutting machine, means for moving lozenge material intermittently through said machine, a pivoted arm provided with a series of cutters, means for moving 90 said arm about its pivot so as to cut the moved material, and means for varying the stroke of said arm.

5. In a lozenge-cutting machine, a belt and means for moving it so as to convey material 95 through said machine a series of cutters supported upon a pivoted arm, means for moving said arm on its pivot so as to bring said cutters in contact with material on said belt, and means for adjusting the stroke of said 100 arm.

6. In a lozenge-cutting machine, devices for moving material through said machine and for furnishing a point at which lozenges may be cut from such material, a reciprocating 105 table laterally removed from such cutting-point, a series of cutters supported upon a pivoted arm, and means for moving said arm about its pivot so as to cut lozenges at the cutting-point and transfer them laterally so 110 as to deposit them upon said reciprocating table.

7. In a lozenge-cutting machine, means for moving lozenge material through said machine, a series of cutters, a delivery-table, 115 means for moving said cutters so as to cut lozenges from the moved material and transfer the cut lozenges laterally to said delivery-table, and means for varying the length of the cutter movement.

Signed by me at Chicago, Illinois, this 22d day of June, 1899.

FRANK H. MARKER.
